AUDIO VISUAL UNIT

Luther M. Sandwick, New York, N. Y., assignor to
Wilcox-Gay Corporation, Charlotte, Mich., a
corporation of Michigan

Application December 30, 1952, Serial No. 22,917

Term of patent 14 years

(Cl. D26—14)

To all whom it may concern:

Be it known that I, Luther M. Sandwick, a citizen of United States, residing at 540 Park Ave., in the city of New York, county of New York, and State of New York, have invented a new, original, and ornamental Design for an Audio Visual Unit, of which the following is a specification, reference being had to the accompanying drawing, forming a part thereof:

Figure 1 is a view in perspective of my novel audio visual unit with the cover removed. The side opposite the handle is plain. The back has the loudspeaker opening shown in Figure 2. The bottom is plain.

Figure 2 is a view in perspective of my novel audio visual unit on a reduced scale with the cover in place and the unit ready to be carried.

The dominant features of my design reside in those portions shown in full lines.

I claim:

The ornamental design for an audio visual unit, as shown and described.

LUTHER M. SANDWICK.
